WAUKEE, WISCONSIN, A CORPORATION OF WISCONSIN

DOOR AND WINDOW CONSTRUCTION

Application filed February 27, 1925. Serial No. 11,920.

Our invention relates to window and door constructions and more particularly to doors such as those in closed automobiles in which a window is vertically slidable.

5 The principal object of the invention is the production of a door of the character described having a novel and simple construction of garnish rail or window sill.

A further object of the invention is the 10 production of a simple and ornamental garnish rail or window sill adapted to engage and hold in position the upholstery or other covering for the window well into which the window is slidable.

15 A further object of the invention is the production of a garnish rail or window sill forming an integral part of the supporting plate or lockboard on which the mechanism for raising and lowering the window is 20 mounted.

Further objects and advantages of the invention will appear from the following description taken in connection with the accompanying drawings:

25 In the drawings illustrating a practical embodiment of the invention:

Fig. 1 is a front elevation of a part of a vehicle door showing our invention applied thereto.

30 Fig. 2 is a horizontal section on the line 2-2 of Fig. 1.

Fig. 3 is a perspective view of a fragmentary portion of the door.

35 Figs. 4, 5 and 6 are similar views showing modifications.

Referring in detail to the several figures of the drawings:

1 indicates the side members of a frame of 40 a door which are provided with guideways 2 therein into which a window pane or sash 3 is vertically slidable. Said window or sash 3 is preferably a frameless pane of glass. It has secured in any desirable manner to the lower 45 edge thereof a U-shaped channel 4. Extending horizontally across the frame and fastened to said side members by suitable screws as shown is a metallic plate or lockboard 4' which may form a portion of the wall of the 50 window well into which the window or sash

3 is slideable, the other wall of the window well being indicated at 5.

6 indicates a bearing or hub which is secured to the plate or lockboard 4' in any manner and which carries a shaft 7 on the inner end of which is secured a pinion 8 and on the outer end of which is secured a rotatable crank or handle 9. An operating arm 10 is also pivotally mounted on the plate or lockwood 4' and is provided with a toothed segment 11 which may be integral therewith if so desired. The outer end of said operating arm 10 is provided with a roller 11' which rides in the channel 4 so that rotation of the crank or handle 9 acts to raise or lower the sash 3 in the guideways 2 depending on the direction of rotation given the crank or handle 9.

We prefer to mount on the righthand side of the plate or lockboard 4' a handle 12 the shank of which is indicated at 13 and the lower end of which is pivoted to the plate 4', said shank extending intermediate said plate and a plate 14 which may be secured to the plate 4' in any desirable manner and which is spaced apart therefrom a certain distance. Said plate 14 is provided with a slot 15 receiving a flange on the rear end of a latchbolt 16 which latchbolt extends through a suitable opening in the righthand side member 1 and into a keeper 17 on a stationary adjacent wall 18. The latchbolt is also provided with a shoulder 19 formed by a slot therein through which the shank 13 extends whereby, when the handle 12 is actuated in the proper direction, the latchbolt will be slid inwardly and retracted from the keeper 17 in an obvious manner.

80 A spring 20 either carried by the plate 14 or the lockboard engages the shank 13 and acts to retain the latchbolt in projected position. The latchbolt is also provided with an arm 21 adapted to be engaged by a roll back 22 in a well known manner and which may be actuated by a handle 23 on the outer side of the righthand side member 1 to retract the latchbolt from its keeper.

85 As indicated in Fig. 3, the upper end of the plate or lockboard 4' is bent inwardly and then outwardly in a graceful curve and 90

as indicated at 24 to form a garnish strip or window sill. The extreme edge of said garnish strip is bent inwardly as indicated at 25 and bites into a covering 26 such as upholstery which forms the inner wall of the window well of the door and which hides the plate or lockboard 4' from view, allowing the crank or handle 9 only to remain exposed to view. Said garnish strip or window sill is also provided with projecting portion 27 pressed out of the metal thereof and which may form a gripping bar to swing the door into closed position. The garnish strip is also provided with a suitable slot as shown in Fig. 2, receiving and supporting the shank 13.

By this construction it will be noted that the plate or lockboard 4' not only forms a support for the window actuating mechanism and the latchbolt and its actuating mechanism but it also itself constitutes the garnish strip or window sill and grippingly engages the covering or upholstery 26 to hold it in proper position.

In the modification illustrated in Fig. 4 a separate wooden rail 28 is provided which is fastened to both side members and which is engaged by the lockboard 4'. A separate metallic garnish strip 29 is also provided which is curved as in the preferred form of the invention, which has an inwardly and upwardly turned flange 30 engaging an outwardly and downwardly turned flange which is integral with the lockboard, the upper end of the upholstery or covering 26 being interposed between the flange 30 and the body of the lockboard.

In the modification illustrated in Fig. 5 the upper end of the lockboard is first turned inwardly to provide a double thickness of metal 32 providing a support for the upper edge of the upholstery 26 and it is then turned inwardly as indicated at 33 to provide an inwardly extending flange. A separate curved plate 34 is also provided to form the garnish strip, the outer edge of which bites into the upholstery 26 as illustrated to hold it in position while the inner edge is provided with a series of hooks 35 hooking under the inner edge of the plate 33 to hold the garnish strip in position.

In the modification of Fig. 6 the upper end of the lockboard is first bent outwardly as at 36 to form a gripping element for the upper edge of the upholstery and it is then bent and curved inwardly as at 37 to provide the garnish strip.

What we claim as our invention is:—

1. In a device of the character described, a frame for supporting a window, a metallic lockboard extending across said frame and carrying a window raising and lowering device thereon, a metallic member integral with said lockboard and extending across said frame to form a garnish strip, said member

comprising a flange turned inwardly and an outwardly extending flange integral with said first-named flange and having an upper curved surface and a covering for said lockboard engaged by and held in position by said garnish strip.

2. In a device of the character described, a frame for supporting a window, a metallic lockboard extending across said frame and having an inwardly turned flange along and integral with its upper edge, and a garnish strip having one edge directly connected to the inner edge of said flange and extending outwardly over said flange and having its other edge adapted to engage and hold a finishing panel in position.

Signed at New York, in the county of New York and State of New York, this 26th day of February, A. D. 1925.

EMIL KOEB.

BERTRAM J. GOLDSMITH.
